STATIONERY SHEET ATTACHING MEANS

Milton C. Stern, Dayton, Ohio, assignor to The Egry Register Company, Dayton, Ohio, a corporation of Ohio

Application September 12, 1940, Serial No. 356,519

6 Claims. (Cl. 282—19)

My invention relates to manifolding stationery and more particularly to a device for providing continuous reloading of manifolding machines with stationery whereby reloading of the machine or attachment is accomplished without disconnecting or otherwise manipulating the manifolding device. This invention is especially useful in providing continuous reloading of manifolding machines such as autographic registers, billing machines, addressographs, typewriters, and attachments therefor.

It is an object of this invention to devise a fastening means for attaching the last set of manifold paper sheets to the leading edge of a new pack of manifold paper forms whereby the machine is kept continuously loaded.

Another object of this invention is to provide a novel continuation sticker for attaching the abutting ends of sheets or webs as used in manifolding machines whereby the leading edge of a succeeding set of paper web forms can be attached to the trailing edge of the paper web passing through the machine.

Another object is to provide a pack of fan-folded continuous webs of manifold stationery with or without carbon sheet removably interleaved therebetween, wherein the leading and trailing edge of the web is feathered and whereby it can be readily joined with the ends of another pack of fan-folded stationery papers so that continuous operation of the machine can be effected.

Another object is to devise a perforated fastening means which is adapted for use in securing the abutting ends of manifold sheets to a succeeding set of manifold papers whereby a continuous web of manifold papers is provided for maintaining the manifolding machine loaded with stationery.

Another object is to provide a web uniting means for fastening one set of manifold paper web forms to a succeeding set which comprise multiple copy sheets having interleaved carbon paper and whereby the attaching means is adapted to assist in bringing about lateral alignment of the edges of the sheets when fastening the ends of the packs together.

These and other objects will more fully appear from the following description taken in connection with the drawings, in which,

Fig. 1 is a perspective view of one embodiment of my invention illustrating the use of a double V-shaped attaching sticker for fastening the ends of one web of manifold paper forms to a succeeding fan-fold pack; the manifold paper sheets

are illustrated in position in a manifolding device which is shown diagrammatically as a fragmentary portion.

Fig. 2 is an enlarged cross-sectional view taken longitudinally of the manifold sheet forms and fastening means illustrated in Fig. 1 and showing the cross-sectional shape of the rupturable sticker employed for holding the ends of the sheets together.

Fig. 3 is a fragmentary plan view of a modification wherein a continuous strip of perforated sticker means is used.

Fig. 4 is a perspective view of another modification wherein the leading and trailing edges of the manifold papers are oppositely chamfered or beveled whereby the ends of the sheets may be spliced together and secured with the use of adhesive or other suitable means providing a flat smooth joint.

Fig. 5 is another modification illustrated in perspective wherein one set of manifold paper sheets is pointed and adapted to be telescopically fitted into the end of the respective sheets of the succeeding pack.

Fig. 6 is still another modification illustrating the use of a perforated sticker strip having chamfered edges for telescopically engaging into the ends of the respective sheets and adhesively securing the same together.

Fig. 7 is another modification showing offset flattened edge construction of the leading and trailing end portions of the manifold paper whereby the ends of the manifold sheets can be attached together to provide a flat, smooth joint.

Fig. 8 is another modification illustrating the use of a narrow perforated tape or adhesive strip for attaching the abutting ends of manifold paper sheets.

Fig. 9 is a similar perspective view showing the use of a separable sticker which is arranged to be secured over and around the sides of the manifold sheets which have their respective ends abutted together and having continuous interleaved carbon paper.

Fig. 10 is a similar view illustrating the use of a similar separable sticker for uniting manifold material having multiple carbon copy sheets in the form of packs detachably adhering at spaced intervals to one side of a continuous manifold.

Fig. 11 is a perspective view of a sticker used as illustrated in Fig. 9.

Fig. 12 is a perspective view of the sticker shown in Fig. 11 when folded in a manner to be positioned around the edges of the manifold sheets for uniting the same as shown in Fig. 9.

Fig. 13 illustrates in perspective a modified form of attaching means similar to that shown in Figs. 11 and 12 but using metal attaching pins for securing the sheets together in place of adhesive.

In the operation of manifolding devices, heretofore, it has been necessary to reload the machine at intervals when the stationary sheet being used becomes exhausted. This requires the opening of a register or manifolding device and re-threading a portion of the manifold papers comprising the new pack and adjusting the machine to bring the manifold paper forms in accurate alignment and adjustment so that the machine can be operated properly. This invention eliminates the necessity of reloading the manifolding machine in this manner and provides for continuous reloading of the manifolding machine with stationery without opening the register or machine.

Referring to Figs. 1 and 2, there is illustrated superimposed manifold paper sheets 15 positioned over writing plate 16 in an autographic register generally designated 18. The manifold paper sheets comprise the spaced forms 20 and are moved transversely of the carbon sheet means 22 which are interleaved between the manifold paper sheets 15. Perforated or weakened sections 23 are provided between the spaced forms 20 as shown in Fig. 1.

As illustrated in Fig. 1, the sheet portion 25 forms the end portion of the manifold paper sheet of one set of forms and the manifold sheet portion 26 comprises the leading manifold sheet portion of a new fan-folded pack designated 28. For attaching the form sheet 25 to the new pack 26, there is provided a double V-shaped sticker means 30 having its broad ends 31 and 32 attached to manifold sheet portions 25 and 26, respectively. The sticker is provided with a perforated or weakened central section 34 whereby the manifold sheet forms 25 and 26 can be readily separated after use.

In order to prevent interference of the sticker with the carbon sheets 22 when the manifold paper webs 15 are moved over the carbon sheets, the edges of the sticker are chamfered as shown at 36. In this way, the paper sheet attaching means 30 can readily pass across the carbon sheet 22 without catching on the edges of the carbon paper and wrinkling or tearing the same. It will be appreciated that the ends of the manifold paper sheets 25 and 26 will be abutted together, aligned and fastened by means of the sticker 30 so that upon operation of the machine no adjustment of the manifold paper sheets relative to the writing plate is necessary.

In the modified fastening means, as illustrated in Fig. 3, a narrow adhesive strip or tape 38 is provided which extends across the width of the paper sheets. The edges 39 and 40 are beveled similarly as shown at 36 in Fig. 2 so that the joint will readily pass over the carbon sheets 22 when operated in the register device as illustrated in Fig. 1. In this instance, the attaching strip means 38 is provided with central perforations 41 so that the adjacent forms 25 and 26 can be readily detached from each other.

In the modification shown in Fig. 4, the manifold sheet 43 comprises a perforated section 44 and an extended portion 46 which is beveled and provided with adhesive 47 so as to receive the beveled portion 48 of the sheet 50 which forms the leading edge of a new set of manifold papers. In this instance, the manifold stationary sheet forms will be provided during manufacture with 75

the attaching portions 46 and 48 so that continuous reloading of the manifolding device can be readily performed by the operator.

In the modification shown in Fig. 5, the manifold paper sheets 43 and 50 are united by dovetailing the leading edge 51 of the sheet 50 and inserting it into the split portion 52 of the sheet 43, the sections 51 and 52 being fastened together by means of adhesive or other suitable material.

10 In Fig. 6, both ends of the manifold sheets 43 and 50 are split so as to receive the perforated double wedged sheet adhesive strip 55 whereby the different sheets are fastened together, providing a smooth joint.

15 In Fig. 7, the superimposed manifold paper sheet form 43 comprises the perforated section 44 and an extending portion 57 which is crimped in such a way as to receive the leading edge of the manifold sheet paper 50 and be adhesively 20 united thereto to form a continuous sheet having no projecting surfaces which would contact the edges of the carbon paper sheet 22 to interfere with the proper operation of the manifold machine.

25 In the manifold fastening means illustrated in Fig. 8, an adhesive strip 59 is utilized for uniting the abutting ends in the manifold paper sheets 43 and 50 similarly as shown in Fig. 3. Perforations 60 in attaching strip means 59 permit ready attachment of the manifold papers during use. In this instance, a continuous carbon sheet is interleaved between the manifold paper sheets 43 and 50. Use is preferably made of Scotch tape which is perforated and positioned over the abutting sheets 43 and 50 to unite them firmly together. This method of attaching the end of the manifold sheet paper with a new pack can be accomplished without preforming or otherwise machining the ends of the sheets forming 40 the pack of stationery.

In Fig. 9, there is illustrated the use of a pre-formed sticker 62 which is adapted to be positioned around the edges of the manifold paper sheet forms 43 and 50 so as to fasten the ends 45 of the sheets together, as heretofore described. The sticker, as shown in Figs. 11 and 12 preferably comprises a rectangular shaped member having creased sections or folds 64, notched end portions 65, perforations 66, and central open 50 section 67. The adhesive material 69 is placed on the underside as shown in Figs. 11 and 12 whereby the sticker can be wetted and attached around the edges of the abutted ends of the sheets 43 and 50 and adhesively secured to the same as shown in Fig. 9. The notched portions 55 65 and perforations 66 will be in registration with the opening between the sheets so that after writing upon the forms 43 and 50, they can be easily separated. In order to prevent the corners of the sticker 62 from engaging the carbon paper sheets 22 or otherwise interfering with the operation of the machine during passage of the manifold webs through the machine, they are beveled as shown at 70. Where the manifold stationery comprises a single web having multiple copy sheet forms detachably secured to one side of the continuous web at spaced intervals as shown in Fig. 10, the end of the pack sheet form 72 may be united to the leading sheet portion 73 of the new pack by bringing the sheets together and pasting the stickers 62 adjacent the sides of the sheets so as to secure them together, as illustrated in Fig. 10. The notched portions 65 and perforations 66 in this instance also will be aligned with the opening between the sheets

so that the forms can readily be detached after use.

In the modification shown in Fig. 13, the member 75 used for attaching the sheets from one pack to the other is substantially the same shape as the sticker 62. In place of the adhesive, there is provided the spaced pin means 77 adjacent to the notched end portion 65 which are adapted to be engaged into the sheets to secure the pack of manifold paper sheets together so that they can be passed through the register or similar manifolding device. By passing the fastening member around the edges of the superimposed manifold sheets as shown in Fig. 9 so as to secure together the top and bottom manifold papers, it is unnecessary to fasten the abutting inner superimposed sheets together as the whole web moves as a unit when the top and bottom sheets are held together.

It will be understood that other suitable means, such as clips, pins, paper stapling means and the like may be provided for fastening the last sheet of paper forms to the first portion of the succeeding set of manifold paper forms.

It will further be understood that the paper sheets will be fastened after they have been properly aligned and abutted together so that it will not be necessary to change the predetermined setting of the manifolding device for advancing the manifold papers a predetermined distance after each writing so that the succeeding form is brought in position over the writing plate of the device.

It will further be understood that this invention is not limited to the particular means described for providing a continuous reloading of manifold stationery in machines of this character and that such modifications as may be necessary to adapt it to varying conditions and uses are within the scope of this invention.

Having thus fully described my invention, what I claim as new and desire to secure by Letters Patent is:

1. As an article of manufacture, a member for attaching manifold papers together in abutting engagement comprising a double V-shaped sticker means having its broad ends attached to respective sheets which are to be secured together, said sticker having a perforated secondary portion in registration with the opening formed by the abutting edges of said sheets whereby said sheets can be readily detached.

2. As an article of manufacture, a member for

attaching manifold papers together in abutting engagement comprising a centrally severable attaching strip or tab for fastening the abutting sheets of said manifold papers together, said fastening means comprising a weakened central section adapted to be arranged in registration with the opening between said abutting sheets whereby said sheets can be separated when fastened together by said strip, said fastening means comprising a double V-shaped fastening means having its broad ends attached to the abutting sheets securing the same together so as to form a continuous manifold paper sheet.

3. As an article of manufacture, an attaching means for fastening the last set of manifold papers to a succeeding set of manifold paper forms comprising a foldable strip having a central weakened section, adhesive material on one side of said fastening means for adhering the paper sheets together, said fastening means having chamfered edges and adapted to be separated along a weakened section to provide for the detachment of the sheets.

4. As an article of manufacture, an attaching means for fastening the last set of manifold papers to a succeeding set of manifold paper forms comprising a foldable strip having a central weakened section, means on said fastening means for detachably securing said sheets together, said fastening means having beveled edges and adapted to be separated along a weakened section to provide for the detachment of the manifold paper sheet forms.

5. As an article of manufacture, a rupturable fastening member for detachably securing the ends of one set of manifold paper sheet forms to another set, said member comprising a double V-shaped adhesive tab having the V-shaped portions united at their apexes to form a readily separable tab for adhesively uniting the ends of manifold paper sheet forms.

6. As an article of manufacture, a rupturable fastening member for detachably securing the juxtaposed ends of one set of manifold paper sheet forms to another set, said member comprising a strip having chamfered outer edges and a central weakened section for severing the strip in half, and comprising means for overlapping and securing said strip to the juxtaposed ends of said paper sheet forms to provide a continuous sheet.

MILTON C. STERN.
